ALARM, LIGHT, AND SAFETY SIGNALING DEVICE

Elmer F. Lynd, Cleveland, Ohio

Application November 13, 1946, Serial No. 709,464

9 Claims. (Cl. 177—339)

1

The object of my present invention has been to devise a novel form of a unit in the nature of an alarm, light and safety signaling mechanism or device particularly designed for use in conjunction with dwelling places, commercial buildings, or the like.

In the carrying out of my invention various objects are attained. In the first place, the device or unit of the present invention provides a bell ringing feature analogous to those commonly in use today for advising of arrival of visitors to a home, apartment, commercial building or the like. Additionally, the unit of the present invention involves provisions whereby on operating the door bell or chime ringing appliance, a light will be put on at the door entrance so that anyone in the dwelling or apartment may readily see who is outside the entrance door, prior to opening of the latter. The light feature referred to is a part of the audible signaling or bell ringing feature of my invention.

A safety objective is achieved also in the operation of my invention. In this connection it is known that in dark districts of cities, quite commonly, persons are often chased by purse snatchers, or persons having a criminal bent, with disastrous results. According to the use of my invention however, it is possible for such persons when pursued, to run up to the entrance of a home or building equipped with the alarm and light signaling unit hereinafter described, to press the door button for operating the audible signaling device, and simultaneously throw on the light provided at the door entrance adjacent preferably to such door button. In this way the entrance of the home or building will be illuminated immediately and at the same time the signal in the form of a door bell or chime alarm will be sounded. Under the above conditions my invention when used in the manner last described becomes a safety device that may often be of utmost value for the protection of the public.

For a full understanding of my invention and the advantages of the same reference may be had to the following detailed description, and to the accompanying drawings, and in the latter:

Figure 1 is a view in front elevation, partly broken away showing the entrance door to a dwelling, apartment or similar building, the invention hereinafter being illustrated as mounted upon one side of the frame of the door similarly to the arrangement customarily found today for door bell units.

Figure 2 is a vertical longitudinal section through the side of the door frame which is

2

equipped with my invention and shows the details of the audible and visual signaling mechanism in the normal unoperated position of the various parts.

5 Figure 3 is a fragmentary view somewhat similar to Figure 2 and showing certain parts of the mechanism illustrated in Figure 2 after the audible signal button has been depressed or pushed in to cause the sounding of the bell chime or other audible signal in the dwelling or building and at the same time put on the light which will illuminate the entrance where the door is located.

10 Figure 4 is a view showing more clearly the expanded position of the disc thermostat by which 15 the parts of the audible and visual signal are restored to normal position, the thermostat being in its expanded condition to normalize the switch lever.

15 Figure 5 is a fragmentary sectional view taken 20 about on the line 5—5 of Figure 3 showing the relation of the switch lever to the stationary switch contact member.

25 Describing my invention specifically I have illustrated in Figure 1 of the drawings, in a somewhat fragmentary manner, the usual entrance to a dwelling, apartment or other building comprising the door frame 1 in which is hung the usual door 2. As seen in the above figure at one side of the door frame 1 is disposed my newly invented 30 unit including a casing 3 equipped at its lower end portion with the push-button 4 for controlling an audible signal or alarm such as the usual door bell or signaling chimes. At its upper portion the casing 3 is provided with a translucent member 5 made of glass or plastic material in the rear of 35 which is disposed a light the rays of which are adapted to pass through the translucent member 5 to illuminate the entrance in which the door marked 2 is mounted, exteriorly thereof.

40 Now referring to Figures 2 and 3 of the drawings particularly it will be observed that the audible signal operating button 6 is the usual plunger type button mounted in a small casing 7 secured to the main enclosing casing 3 and projecting inwardly from the front side of the latter, the button 6, or plunger, may be normally maintained in its outward position by means of a coil spring 8. The button 6 has an inner stem or plunger portion 9 adapted to engage and move the 45 lower enlarged end 10 of a pivoted switch lever 11, the latter having the pivotal mounting 12 intermediate its ends, and adapted to cooperate at a point between the pivot 12 and the enlarged end 10 with a stationary contact plate 13 secured in 50 55 a suitable manner within the casing 3.

The inner end of the lower enlarged portion of the switch lever 11 is adapted to also co-operate as a circuit closing member with the movable contact member 14 suitably supported in a mounting plate 15 which may be of round form the general arrangement of the parts 14 and 15 being somewhat similar to the ordinary method of mounting of a bell ringing button such as now used on home or at the entrances to apartments or buildings.

As seen in Figure 2 the movable contact operating member 14 has an electrical contact portion 16 at its inner extremity to engage with the stationary electrical contact 17. As illustrated the members 14 and 17 are so related that when the parts 16 and 17 are moved together an electric circuit including these parts will be closed. This electrical circuit comprising conductors 18, 19 and 20 suitably connected up with a transformer 21, also includes the audible signal alarm or bell comprising the chimes 22 according to the showing in my drawings. Of course, there may be substituted for the chimes 22 any ordinary electric signaling bell such as quite commonly used today for bell purposes in homes.

The electric circuit means referred to also includes a conductor 23 connected with the stationary contact member 13, a conductor 24 connected with the switch lever 11 and extending to the light bulb 26 and a conductor 25 leading from the light bulb 26 to the transformer 21. The electric circuit means as shown is conventional and may be varied of course in accordance with the skill of those versed in the electrical art.

At its upper end the switch lever 11 is equipped with an abutment lug 27 which abutment 27 is disposed normally spaced from but opposite the movable stem member 28 of an expansible disc thermostat 29 mounted in suitable supporting bracket means 30 and adapted for adjustment to vary its time of operation, in the customarily conventional manner of its construction. The thermostat means referred to may be of any general type such as commonly in use today and is well known. This thermostat is operated by heat generated within the casing 3 when the light 26 is put on and the disc of the thermostat is expansible after the manner portrayed in Figure 4, whereby to effect a lengthwise movement of the actuating stem portion 28 of the thermostat for a purpose now to be set forth.

With the above construction of my mechanism in mind the operation thereof is as follows:

A person upon approaching the entrance to the dwelling that may be equipped with my invention, wishing to signal his arrival or use the unit of my invention as a safety device, will depress the plunger button 6 and thereby cause a swinging action of the lower large portion 10 of the lever 11 to move this switch lever into contact with the movable button or contact actuating member 14, the size and weight of the lever 11 will be sufficient for maintaining the same in the operated position mentioned, and illustrated by Figure 3 so long as the member 6 is pressed inward under which conditions of course the audible signal 22 will be in operation to signal or alarm the persons in the dwelling.

Since the lever 11 controls the light circuit including the light bulb 26, when the said lever is in the position of Figure 3 it will make contact with the stationary contact member 13 and put on the light 26 to illuminate the entrance, simultaneously with the operation of the audible signal.

If the pressure on the button of plunger 6 is

released it will return to its normal outward position as shown in Figure 3 by the action of the spring 8. The lever 11 however will not return to its position of normal status as indicated in Figure 2 but will remain in contact with the contact 13, maintaining the light 26 on, until sufficient heat is generated in the casing 3 to act upon the thermostat 29 for expanding the thermostat in the manner shown in Figure 4. On such expansion the thermostat actuating stem 28 will strike the abutment member 27 while the latter is in position as shown in Figure 3 and thereby move the lever 11 with a rocking movement so as to disengage the lever from the stationary contact 13 at which time the bell or audible signal 22 will cease operating and the light 26 will go out.

The effect of the light 26 of course is to sufficiently illuminate the entrance of the dwelling so that it affords a zone of safety for a person who is being pursued by anyone with criminal intent. Thieves and robbers do not pursue their criminal tactics of course in a place where there is plenty of light and therefore, the advantages of my unit as a safety mechanism will be clearly apparent.

As regards to thermostat 29 it may of course be adjusted to maintain the audible and visual signaling means in operation for a period of several minutes more or less as desired. Moreover in the action of the thermostat 29 as its condition returns to normal after expansion in the manner of Figure 4, it will become inoperative, at which time the lever 11 will be restored to non-operating position, and the parts will be in the positions thereof as shown in Figure 2.

If desired and my construction of unit, readily so permits, the initial movement of expansion of the thermostat 29 may separate the lower large contact portion of the switch lever 11 from the push button 6 so as to stop the ringing of the audible alarm or bell means sometime prior to the disengagement of the lever 11 from the stationary contact 13. Thus the persons in the dwelling will not be annoyed by a continuous ringing of the audible signal, notwithstanding that the light 26 is maintained operative or on for a considerable period subsequent to the ringing of the bell advising the occupants of the dwelling of the arrival of the person exterior to the entrance thereof. The contact 13 is of sufficient size so that switch lever 11 will engage contact 13 during a substantial portion of the pivotal movement of lever 11 and thus lever 11 will remain in engagement with contact 13 for a certain period after disengagement of contacts 16 and 17 due to the action of spring 31. If desired, the spring 31 may be made strong enough to cause disengagement of contacts 16 and 17 irrespective of the action of thermostat 29. A suitable spring such as found in ordinary bell buttons designated 31 will restore the pressure member 14 to its normal position discontinuing the sounding of the audible signal, when the initial movement of the lever 11 has been compelled by the action of the thermostat 29 in the manner described.

As a safety measure it may be desired at times to maintain the bell or audible signal 22 in continuous operation, while under other conditions of home use of the unit of this invention, the operation of preliminarily discontinuing the action of the audible signal while maintaining the entrance illuminated by the light 26, will be desirable. Either method of use of my invention may be re-

sorted to within the purview of my claimed subject matter.

It will be obvious that under some conditions my unit may be built so that the casing 3 and the various parts of the mechanism therein contained, except the parts 15, 14 and 31 may be built as a unit so that such unit may be applied to an ordinary door bell system that may comprise the parts 15, 14 and 31 already mounted upon a door frame. Also under some conditions it may be desirable that the casing 3 as an entirety be made of a translucent substance such as glass or Lucite or the like and mounted bodily upon the door frame in such condition so that the entire casing will be illuminated when the light 26 is put on. These are variations of my invention contemplated within the purview of the same as circumscribed by the scope of my appended claims.

Having thus described my invention what I claim as new and desire to secure by Letters Patent of the United States, is:

1. In a signaling device, in combination, an entrance to a dwelling, apartment, or the like, comprising a door frame, a door therein, a light arranged to exteriorly illuminate the entrance, an audible signal interiorly of the entrance, and means to simultaneously operate the light and audible signal, including a control device, means for actuating said first means, said control device comprising means for maintaining the audible signal in operation and the light on after actuation of said actuating means is discontinued, and means to automatically discontinue operation of said audible signal and shut off the light after a predetermined time subsequent to operation of said operating means.

2. In a signaling device, in combination, an entrance to a dwelling, apartment, or the like, comprising a door frame, a door therein, a light arranged to exteriorly illuminate the entrance, an audible signal interiorly of the entrance, means to simultaneously operate the light and audible signal, including a control device, said control device comprising means for actuating said first means, means for maintaining the light on after actuation of said actuating means is discontinued, and means to automatically shut off the light after a predetermined period of time subsequent to operation of said operating means.

3. A signaling device as claimed in claim 2, wherein the last means comprises a thermostatic device operable by the heat of said light.

4. In a signaling device, in combination, an entrance to a dwelling, apartment, or the like, comprising a door frame, a door therein, a light arranged to exteriorly illuminate the entrance, an audible signal interiorly of the entrance, means to simultaneously operate the light and signal, including a control device comprising means for actuating said first means, means for maintaining the light on after actuation of said actuating means is discontinued, and means to automatically discontinue operation of the signal after a predetermined period of time subsequent to operation of said operating means, and subsequently to shut off the light after a predetermined period of time following discontinuance of operation of said signal.

5. In a signaling device, in combination, an audible signal, a light, and means to operate the light and signal, including a control device to maintain the light on for a predetermined period of time after actuation of the operation effecting means, said control means comprising switch means for operating said signal, switch means for operating said light, actuating means cooperable with one of said switch means for causing switch closing operation thereof, said last mentioned switch means being operative to maintain switch closing condition when so operated, a thermostatic device associated with the last mentioned switch to restore the latter to open condition, the last mentioned switch means being cooperable with said other switch means to close the latter, and spring means operable to restore said other switch means to open condition.

6. In a signaling device, in combination, an audible signal, an electric lamp, and means to simultaneously light the lamp and operate said signal, including a control device, means for actuating said first means, said control device comprising means for maintaining the lamp lighted after actuation of said actuating means is discontinued, and means to automatically shut off the lamp after a predetermined period of time subsequent to operation of said operating means.

7. A signaling device as claimed in claim 6, wherein the last means comprises a thermostatic device.

8. In a signaling device, in combination, an audible signal, an electric lamp, and means to simultaneously operate said lamp and said signal; including a control device, means for actuating said first means, said control device comprising means for maintaining the audible signal in operation and the lamp illuminated after actuation of said actuating means is discontinued, and means to automatically discontinue operation of said audible signal and shut off the lamp after a predetermined time subsequent to operation of said operating means.

9. In a signaling device, in combination, an audible signal, an electric lamp, and means to simultaneously operate the lamp and signal, including a control device, actuating means for said first means, said control device comprising means for maintaining the lamp illuminated after actuation of said actuating means is discontinued, and means to automatically discontinue operation of the signal after a predetermined period of time subsequent to operation of said operating means and subsequently to shut off the lamp after a predetermined period of time following discontinuance of operation of said signal.

Certificate of Correction

Patent No. 2,473,436.

June 14, 1949.

ELMER F. LYND

It is hereby certified that errors appear in the printed specification of the above numbered patent requiring correction as follows:

Column 5, lines 44 and 45, claim 2, strike out the words "said control device comprising" and insert the same after the word and comma "means," in line 46, same claim; and that the said Letters Patent should be read with these corrections therein that the same may conform to the record of the case in the Patent Office.

Signed and sealed this 15th day of November, A. D. 1949.
